UNITED STATES PATENT OFFICE.

HENRY BROWN, OF COLUMBUS, OHIO, ASSIGNOR OF TWO-THIRDS TO D. D. CAROTHERS AND JOSEPH P. JOHNS, BOTH OF SAME PLACE.

JOURNAL-BEARING.

SPECIFICATION forming part of Letters Patent No. 363,204, dated May 17, 1887.

Application filed December 9, 1886. Serial No. 221,053. (No model.)

To all whom it may concern:

Be it known that I, HENRY BROWN, of Columbus, in the county of Franklin and State of Ohio, have invented certain new and useful Improvements in Journal-Bearings; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to journal-bearings, especially locomotive or similar bearings, which, when originally or newly constructed, are each provided with a small groove in its inner surface, with which communication is had with its outer surface by means of sprue-holes, through which Babbitt or other metal alloy is poured to fill said groove to the level of the interior surface. As is well known, these brasses or bearings soon wear on their inner surfaces, becoming thus too large to properly fit the journals they support, and are consequently worthless, or, at least, only fit for the melting pot.

The object of my invention is to enable these brasses to be renewed, as it were, or utilized again and again for their original purpose, thus effecting great economy in their use.

My invention consists in the reconstructed or renewed journal-bearing hereinafter fully described, and specifically pointed out in the claim.

In the drawings, Figure 1 is a perspective view showing the interior of a journal-bearing reconstructed or rendered capable of again being used according to my invention. Fig. 2 is a transverse vertical section therethrough. Fig. 3 is a plan view of the same, and Fig. 4 is a plan view of the same in a slightly-modified form. Fig. 5 is a cross-section of the bearing, showing it in the process of having the grooves or cavities filled with new metal for the renewed bearing.

Like letters of reference mark the same parts wherever they occur in the various figures of the drawings.

Referring to the drawings by letters of reference, A is the bearing, whose inner surface, when new, is of the exact curvature of the

journal (represented by dotted lines at *a* in Fig. 2) which it is to support, or, technically speaking, "of the same set as the journal." *b* is a groove formed in the inner surface of the journal-box when it is cast, (originally,) from the bottom of which sprue-holes *c* lead to the outer surface of the brass or bearing. This groove, through the medium of the holes *c*, is filled with molten Babbitt metal or other metal alloy to the level of the inner surface, which is, as before stated, shown by the dotted lines at *a* in Fig. 2.

After the bearing has been used for some time the interior surface wears away and its interior curvature no longer coincides with the exterior curvature of the journal, and consequently, having become loose, it is no longer fit for use as a bearing. The Babbitt metal or other alloy being fusible at a much lower temperature than the brass, the portion thereof remaining in the groove *b* may be melted out, leaving a worthless brass. This I propose to renovate or restore to utility by my invention, as follows: I cut in it a dovetail or other undercut groove, as shown at *d* *e*, the portions *d* and *e* of said groove being longitudinally of the bearing, and also other parts transverse thereto, thus forming in effect a continuous groove having four sides—two longitudinal and two transverse. I then cast in said grooves, pouring in through sprue-holes in the bearing communicating with the grooves, as in Fig. 5, or in the end of the longitudinal grooves *d* or *e*, which may be extended to the end of the brass for that purpose, as shown at *h* in Fig. 1, Babbitt metal or other suitable metal alloy, forming a rib, in a rectangular form, as shown at *d' e' f' g'*, projecting inward beyond the worn interior surface, and slightly beyond the original interior line of the brass when new, said rib being shaped in a suitable mold, upon which the old brass is placed, as in Fig. 5, while casting. When cool, this brass, having the rib, as before stated, is taken from the mold and the interior surface of the rib trued to the curvature of the journal which it is to bear. The old brass is now ready for use, and is in as good if not better condition than it was originally.

The space included within the rib *d' e' f' g'* acts as a reservoir for a lubricant, and the bearing will be equally as good and perfectly

operating as it was originally, and will last a much longer time and be more perfectly lubricated at all times.

The expense attending the renovation or re-utilization of these old brasses is insignificant, and no specially skilled labor is necessary to properly perform the operation, while, as readily seen, the saving will be immense. The old brasses can be again and again renovated, the groove being cleared of Babbitt metal, &c., after each wearing down, by melting it out, when it can again be filled and the brass again used.

The rib may be of a modified shape, cast in correspondingly-modified grooves, as shown at *i i i* in Fig. 4, in which case the longitudinal portions are connected by intermediate transverse sections, forming more alloy surface for the journal to bear upon, and the ribs ²⁵ may be regulated in width to suit the weight to be imposed upon them.

Having thus fully described my invention, what I claim, and desire to secure by Letters Patent of the United States, is—

The brass for journal-boxes herein described, ²⁵ provided with a continuous undercut groove consisting of two longitudinal and two transverse portions, and the continuous rib cast in said groove and projecting therefrom beyond the interior worn surface of the brass, whereby ³⁰ is formed a new bearing and a lubricant-reservoir, as set forth.

In testimony that I claim the foregoing as my own I affix my signature in presence of two witnesses.

HENRY BROWN.
